United States Patent Office

Des. 193,890
Patented Oct. 23, 1962

193,890

BOAT BOARDING LADDER

Frederick N. Canning, 1121 Puritan Road, and Walter L. Canning, 550 N. Glenhurst Ave., both of Birmingham, Mich.

Filed Mar. 7, 1960, Ser. No. 59,625

Term of patent 14 years

(Cl. D15—8)

FIG. 1

FIG. 2

FIG. 3

FIG. 1 is a face elevational view of the boat boarding ladder embodying our new design.

FIG. 2 is a side elevational view of the ladder seen in FIG. 1; and

FIG. 3 is a reduced perspective view of the ladder seen in FIGS. 1 and 2.

We claim:

The ornamental design for a boat boarding ladder, as shown.
